Ms. 1655

Samuel H. Ransom, of Albany, N.Y.
Letters Patent No. 1655, dated Sept. 9, 1862.

The schedule referred to in these Letters Patent and making part of the same.

To whom it may concern,

Be it known that I, Samuel H. Ransom, of the city of Albany and State of New York, have produced a new and original design for the plates of an elevated Oven Cook Stove, which stove is named the Broadside; and I declare that the annexed delineations are full and accurate representations of the ornamental design on the different plates.

The plates not shown are of the same design as those annexed.

Dec. 1655

A. represents the oven door.

B. " the oven front or back.

C. " the front of the stoves, with doors.

D. " the side plate of the body of the stove

these with other plates forming when mounted together the stove
called the Broadside.

What I claim as my production and desire to
secure by Letters Patent, is the combination and arrangement of
ornamental figures and forms represented in the accompanying photo-
graphs, forming together the ornamental design for an elevated
oven cook stove.

Witnesses,

James A. Greig,
A. Spushack
